UNITED STATES PATENT OFFICE.

EDWARD FULDA, OF NEW YORK, N. Y.

METAL DOOR CONSTRUCTION.

1,328,918.

Patented Jan. 27, 1920.

Application filed January 19, 1918. Serial No. 72,900.

To all whom it may concern:

Be it known that I, EDWARD FULDA, a citizen of the United States, and a resident of New York, in the county of New York and State of New York, have invented certain new and useful Improvements in Metal Door Constructions, of which the following is a specification.

My invention relates to the construction 10 of doors made wholly or principally of metal.

The object of my invention is to produce a door that shall be extremely rigid and strong and that may be readily constructed 15 wholly from sheet metal and from ordinary commercial forms of bar iron.

To these ends my invention consists in the improved construction herein described and illustrated in the accompanying drawings 20 wherein I have shown my invention as embodied in a door made in two sections each comprising a metal frame composed of a flanged metal bar and having the door or panel side consisting of sheet metal fastened 25 to a flange of said bar. For convenience in the following description the said flanged metal bars will be referred to indifferently as angle iron or as T-iron, those being the ordinary commercial terms used to describe 30 respectively those forms of bar iron in which the bar has, in the one case, a single flange projecting to one side thereof to make an angle or L-bar and in the other case has flanges projecting from opposite sides thereof and constituting together the head of a T.

In constructing a door according to my invention, I preferably employ for at least one section or side of the door the L form or form having one flange only, since in the 40 preferred construction the bar itself is made to constitute one edge of the door or panel.

In the accompanying drawings Figure 1 is a perspective view of one-half of the door and Fig. 2 is a perspective view of the other 45 or counter part section.

Fig. 3 is a cross-section through the completed door.

Fig. 4 is a cross-section through the door near its edge when both halves are made of 50 angle iron.

Referring first to Fig. 2, 1 indicates a metal frame consisting of T-iron bent or made up into a shape conforming to the outline of door panel constituting the completed structure and having a sheet metal facing 2 constituting one side of the door or panel

fastened to the flange portion 1' of said frame in any desired way as for instance by electric spot welding of the bar to the inside of the sheet metal facing. 60

3 indicates a strengthening diagonal of the frame made preferably of T-iron for greater strength. The sheet metal facing 2 projects preferably beyond the edges of the flange of the metal frame 1 to constitute a 65 ledge, as indicated at 2', which receives the edge of the metal bar constituting the frame of the opposite section and constituting also the edge of the completed door or panel. Also the edge of a sheet metal facing is 70 flush with the edge of the completed door and is flush with the surface of the counterpart section as will be presently seen and as shown in the section Fig. 3.

Referring to Fig. 1, 4 is the frame of the 75 opposite or counter part section, said frame being made preferably of angle iron while 5 indicates a sheet metal facing secured to the flange 4' of said angle iron bar. The bar proper 4 constitutes the outer edge of 80 the completed door or panel, and the sheet metal plate or facing 4' has its edge substantially flush with the face of the bar 4 as shown in Fig. 3.

6 indicates a strengthening diagonal made 85 of T-iron fastened in the frame 4. At the corners of the frame 4 and the ends of the diagonal a space is left between the ends of said diagonal and the corner to allow the corresponding corners of the section Fig. 1 90 to slip down into position when assembled.

In assembling the strengthening diagonals cross one another and each is recessed at the crossing, as shown, to allow assembly. When the sections are assembled the main 95 or bar portion of one frame, for instance frame 1, nests within the angle bar 4 constituting the frame of the other section, said angle bar 4 then forming the edge of the structure. The edge of the bar 4 itself engages or makes joint with the projecting portion 2' of the sheet metal facing 2 upon the counter part section embodying the frame 1 and makes a clean finish for the 100 edge of the door or panel. 105

As shown in Fig. 2, the bar constituting the frame is slightly cut down at the corners to a depth substantially equivalent to the thickness of the flange upon the frame in the opposite section of the door and permits 110 a perfect fitting of the sections together, while the ends of the diagonal in the section

shown in Fig. 2 are correspondingly cut away to a thickness substantially equal to the thickness of the flanges in the portions of frame and diagonal upon the opposite 5 or counter part section, Fig. 1, for a similar reason.

In order to secure a perfectly flush finish of the face of the door and with perfect concealment of the means for fastening the 10 parts together welding or brazing is used for securing the sheet metal facing to the flanges, the welding or brazing being done on the inside where the sheet metal facing 15 engages the flange of the frame. The sections or counter parts, when assembled and secured together, form a strong, rigid, and perfectly flat door or panel.

It is perfectly obvious that moldings can 20 be paneled on the face of the plane sheets 2 and 5 or that the said sheets may be formed with ornamental panels or moldings struck up or impressed therein without in any way departing from the essentials of the construction constituting the invention.

25 As shown in Fig. 4 the frame for both halves may be made from angle iron. In this instance the metal bar 1 for the frame of one side is substantially the same as the bar 4 for the frame of the other side excepting that the width of the bar 1 is less 30 than the width of the bar 4 by the thickness of the flange 4' for the latter, thus permitting the frames to be nested one within the other without any substantial space between 35 1 and 4, such as is shown in Fig. 1, while at the same time permitting the edge of 4 to meet the inside of the plate 2'. Also, as will be seen, the web part of the flanged bar 1 engages by its edge against the inside of 40 the flange 4' of the flanged bar 4.

What I claim as my invention is:—

1. In a metal door or panel made in sections, the combination substantially as described of an outer frame composed of a 45 flanged metal bar constituting the outer edge of the complete door and a sheet metal facing constituting a side of the door or panel and fastened to the outer face of the flange of said bar with an edge of the sheet 50 metal flush with the face of the portion of bar constituting the edge of the door and a counterpart frame of angle iron nested within the first and having a door side of sheet metal secured to the outer face of the 55 flange thereof with an edge projecting to receive the edge of the bar constituting the

edge of the door and within which it is nested.

2. In a metal door or panel made in sections, the combination substantially as described of an outer frame composed of a flanged metal bar constituting the outer edge of the complete door and having a sheet metal facing constituting a side of the door or panel and fastened to the outer face 60 of the flange of said bar with an edge of the sheet metal flush with the face of the portion of bar constituting the edge of the door and a counterpart frame of T iron nested within the first and having a plate of sheet 65 metal constituting the door side secured to the outer face of the head of the T with the sheet metal edge flush with the outer edge of the door.

3. In a metallic door or panel, the combination substantially as described, of two frames combined to constitute the outer frame or edge of the door and consisting respectively of flanged metal bars one nesting within the other, the bar of one frame 80 constituting the extreme outer edge of the door and having a sheet metal plate constituting the door face secured to the outer surface of a flange thereof and with a metal plate edge flush with the surface of 85 the bar which constitutes the door edge while the other or counterpart frame consisting of a flanged metal bar has a sheet metal door face secured to the outer surface of a flange thereof and projecting 90 slightly beyond the same to have its edge flush also with that face of the first-named bar which constitutes the outer edge of the door.

4. A metal door made in sections, each 95 comprising a flanged metal frame having a flanged strengthening diagonal, said frames nesting one within the other with the diagonals crossing and each recessed at the point of crossing and each frame or section 100 having a door side or panel fastened to the flange of the metal bar by a weld between the outer face of said flange parallel with the face of the door and the inside of the panel.

Signed at New York, in the county of New York and State of New York this 4th day of August, A. D. 1915.

EDWARD FULDA.
